UNITED STATES PATENT OFFICE.

WILLIAM S. WYLAND, OF LAKE FORK, ILLINOIS.

CONVEYING MECHANISM.

No. 895,529.

Specification of Letters Patent. Patented Aug. 11, 1908.

Application filed October 26, 1907. Serial No. 399,337.

To all whom it may concern:

Be it known that I, WILLIAM S. WYLAND, a citizen of the United States, residing at Lake Fork, in the county of Logan and State of Illinois, have invented certain new and useful Improvements in Conveying Mechanisms, of which the following is a specification.

This invention relates to baling presses and more particularly to an attachment designed to convey straw or hay to the press from the stack or other storage place, and has for its object to provide such an adjunct which will be adaptable to use with any press, and which will be adjustable to bring material from any direction.

Another object is to provide a means for increasing the length of the conveyer when desirable, by means of detachable and operative sections.

Another object is to provide such a structure which may be readily taken apart and stored within a small space.

Other objects and advantages will be apparent from the following description, and it will be understood that changes in the specific structure shown and described may be made within the scope of the claims without departing from the spirit of the invention.

In the drawings forming a part of this specification, and in which like numerals of reference indicate similar parts in the several views, Figure 1 is a side view of the conveyer attached to the side of a press in operative position, with one detachable extension in place, Fig. 2 is a sectional view through the base and bolster at right angles to Fig. 1, Fig. 3 is a top view of the invention, Fig. 4 is a sectional view of the elevator section at the lower end thereof, Fig. 5 is a detail plan of the elevator section, Fig. 6 is a longitudinal section on the line 6-6 of Fig. 3. Fig. 7 is a sectional view of the upper and outer corner of the frame, longitudinally thereof, showing the mounting and operative connections of the bolster. Fig. 8 is a top view of the outer end of the frame with the bolster removed, showing the construction of the collar 30. Fig. 9 is a detail of the power wheel and clutch, and Fig. 10 is a plan view of the inner end of the conveyer section, showing the opening 43 and the screen 44.

Referring now to the drawings, there is shown the side of a baling press 10, to which

the base portion of the present conveyer is removably secured, as shown in Fig. 1. The base portion consists of a rectangular framework A, having a lower floored portion 15 and an upper floored portion 16. Eyes 18 are secured at the inner end of the base, projecting therefrom for detachable connection with brackets 19 carried by the press 10, it being understood that the attachment is effected by means of pins 17.

A horizontal shaft 20, extending longitudinally of the frame, is carried by the bearings 23 and 24 borne on the floor 15. A power wheel 21 is loosely mounted on the shaft near its inner end, and adjacent thereto on the shaft there is a clutch 21', operated by a rod H and foot lever K, the clutch making operative connection between the shaft and power wheel when operated. A vertical shaft 25 is mounted at the outer end of the frame A and extends thereabove being fitted in a bearing 29 in the floor 16 and its lower end held in operative position by a bracket bearing 26' secured upon the floor 15. The shaft 25 carries at its lower end a beveled gear 26 meshed with the gear 22, and near its upper end a beveled gear 27 above the floor 16, the end of the shaft projecting upwardly beyond the gear to form a pivot 28 for a bolster B, as will be described. Secured horizontally upon the top of the frame A with the shaft 25 at its center, there is an annular metal collar 30.

The collar 30 supports the bolster B, which consists of a bed portion 31 pivoted at its center on the pivot portion 28 of the shaft 25 and carrying at its opposite ends uprights 32 and 33 having alining slots 34 in their upper ends to receive the supporting trunnions of an elevator section C, as will be described. A shaft 35 is mounted longitudinally in the bolster, being journaled in the upright 33 and extending toward the center of the bolster, being supported at its inner end by a bearing 36, secured upon the bed 31. Keyed to the outer end of the shaft 35, outwardly of the upright 33, there is a gear 37, and at the inner end there is keyed a beveled gear 38 adjusted to mesh with the gear 27 through a slot 39 in the bed 31 of the bolster.

An elevator section C is inclined upwardly from the ground to lie with its upper end between the uprights 32 and 33 of the bolster B, and includes two side pieces 40 and 41, carrying between them a floor 42, having an opening 43 near the upper end and extending

the full width of the floor. Outwardly projecting trunnions D are secured in the side pieces 40 and 41 near their upper ends and are removably engaged in the slots 34 of the uprights 32 and 33. A screen 44 is fitted over the opening 43 for a purpose to be hereinafter described. Extending between and carried revolvably in the side pieces 40 and 41 at their opposite ends there are two shafts 45 and 46 having sprockets 47 secured near each of their ends inwardly of the side pieces, and having upper and lower gears 48 and 49 respectively, keyed on their outer ends outwardly of the side piece 41, the gear 48 being of a sufficient diameter to engage the gear 37 of the bolster B when the elevator section is adjusted to lie with its trunnions D engaged in the slots 34. Endless chains 50 are engaged around the sprockets 47, having rods 51 secured to and extending between them for sliding movement along the floor 42 when the sprockets 47 are rotated, a conveyer being thus formed. Two vertical legs 52 are secured upon the outer sides of the pieces 40 and 41 near their lower ends, and have upwardly extending end portions E in which there are formed slots 53 intended to receive the supporting trunnions F of a horizontal extension section G, as will be described. A gear 54 in mesh with the gear 49 is mounted revolvably on the adjacent leg 52.

The detachable extension G is constructed in a manner similar to that of the elevator section C, with the exception that neither opening nor screen are provided to correspond with those indicated at 43 and 44. This extension lies with its supporting trunnions F engaged in the slots 53 of the legs 52 of the elevator section C, and a gear 48', corresponding to the gear 48, meshed with the gear 49, the outer end of the section resting upon legs 52' similar to those 52.

A fastener M is secured to the frame A immediately below the bolster B, for engagement with the latter to hold it against disengagement. By removing the lower pins 17, the base may be turned upwardly and backwardly until it rests across the top of the press, the bolster being suspended outwardly thereof, so that the press and attached parts may be moved simultaneously.

It will be seen that the present conveyer may be attached to the side of a press, and power connections made by means of the power wheel 21. The elevator and attached sections may be extended in any direction, and as many extension sections may be used as the power available and the structural strength of the mechanism will permit.

60 By reason of the movement imparted to the rods 51 through the shafting and gears, hay, straw and similar material may be brought from any point within a considerable radius and elevated conveniently for introduction into a press, thus obviating a

large amount of hand labor which would be required to handle the material with forks or to shift the press.

The screen 44 will allow all grain that may still be retained loosely in the straw to drop through the opening 43 in the floor of the elevator section and into a suitable receptacle.

It will be seen that when it is desired to move the conveyer, it may be accomplished with great ease by removing the several parts separately, the extensions, elevator section and bolster simply requiring to be lifted out of engagement with the parts which support them. It will be seen, also, that very little space, comparatively, will be occupied by the parts when stored.

What is claimed is:

1. In a mechanism of the class described, the combination with a supporting frame of a vertical shaft extending thereabove, means for rotating the shaft, a bolster detachably pivoted on the upwardly extending portion of the shaft, a shaft carried by the bolster, disengageable operative connections between the shaft in the bolster and the vertical shaft said connections being arranged for automatic disengagement simultaneously with the disengagement of the bolster from the shaft, a conveyer detachably connected with the bolster, and disengageable operative connections between the shaft in the bolster and the conveyer, said connections being arranged to engage automatically when the conveyer is brought into engagement with the bolster.

2. In a mechanism of the class described, the combination with a supporting frame of a vertical shaft extending thereabove means for rotating the shaft, an annular metal collar mounted upon the frame to form a turntable having the shaft at its center, a bolster removably mounted upon the collar in pivotal engagement with the upwardly extending portion of the shaft, a shaft carried by the bolster, disengageable operative connections between the shaft in the bolster and the vertical shaft said connections being disposed and arranged for automatic disengagement simultaneously with the removal of the bolster from the collar and shaft, a conveyer detachably connected with the bolster, and disengageable operative connections between the conveyer and the shaft in the bolster, said connections being disposed and arranged for automatic disengagement simultaneously with the disconnection of the conveyer from the bolster.

3. In a mechanism of the class described, the combination with a supporting frame of a vertical shaft extending thereabove, means for rotating the shaft, a bolster removably mounted on the frame and pivoted on the upwardly extending portion of the shaft, uprights having alining slots in their upper ends

120
110
115
120
125
130

and carried at the opposite ends of the bolster, a horizontal shaft carried by the bolster, disengageable operative connections between the horizontal shaft and the vertical shaft, an elevator having supporting trunnions removably engaged in the slots of the uprights, disengageable operative connections between the elevator and the horizontal shaft, legs secured on opposite sides of the elevator at its opposite end from the bolster and arranged to rest upon the ground said legs having upwardly extending end portions having aligned slots therein, a horizontal conveyer extension having supporting trunnions removably engaged in the slots of the legs and having at its opposite end legs secured on opposite sides thereof similar to the first mentioned legs, and disengageable operative connections between the horizontal conveyer extension and the said first named elevator.

4. In a mechanism of the class described, the combination with a vertical shaft of a beveled gear keyed thereto near the upper end, a bolster removably pivoted on the upwardly extending portion of the shaft above the gear and having a slot extending vertically therethrough adjacent to said gear, a

shaft carried by the bolster, and a beveled gear keyed to said shaft and engaged in said first named gear through the slot.

5. In a mechanism of the class described, the combination with a supporting frame of a horizontal shaft, means for rotating the shaft, a trip mechanism arranged to disengage the shaft from the rotating means, a foot lever arranged to operate the tripping mechanism, a vertical shaft extending above the frame, operative connections between the horizontal shaft and the vertical shaft, a bolster removably pivoted upon the upwardly extending portion of the vertical shaft, a shaft carried by the bolster, operative connections between the shaft in the bolster and the vertical shaft, a conveyer detachably connected with the bolster, and operative connections between the conveyer and the shaft in the bolster.

In testimony whereof I affix my signature, in presence of two witnesses.

WILLIAM S. WYLAND.
